US00D935268S

(12) **United States Design Patent** (10) **Patent No.:** **US D935,268 S**
(45) **Date of Patent:** **** Nov. 9, 2021**

(54) **LID**

(71) Applicant: **YETI Coolers, LLC**, Austin, TX (US)

(72) Inventors: **Dustin Bullock**, Austin, TX (US);
Steve Charles Nichols, Austin, TX (US);
Edward Abante, Austin, TX (US);
Evan Goldberg, Austin, TX (US)

(73) Assignee: **YETI Coolers, LLC**, Austin, TX (US)

(**) Term: **15 Years**

(21) Appl. No.: **29/751,504**

(22) Filed: **Sep. 22, 2020**

Related U.S. Application Data

(63) Continuation of application No. 29/667,017, filed on Oct. 17, 2018, now Pat. No. Des. 897,151.

(51) **LOC (13) Cl.** **07-99**

(52) **U.S. Cl.**

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a top, front, right perspective view of a lid showing our new design in its exemplary environment;

FIG. 9 is a top, front, right perspective exploded view of a lid showing our new design;

FIG. 10 is a front view thereof;

FIG. 11 is a right side view thereof;

FIG. 12 is a rear view thereof;

FIG. 13 is a left side view thereof;

FIG. 14 is a top view thereof;

FIG. 15 is a bottom view thereof; and,

FIG. 16 is a top, front, right perspective exploded view of a lid showing our new design in its exemplary assembly.

The broken lines depicting the remainder of the lid show features that form no part of the claimed design. The broken lines in FIGS. 8 and 16 depict the lid in its exemplary assembly that forms no part thereof.

1 Claim, 16 Drawing Sheets
